UNITED STATES PATENT OFFICE

WILHELM HÖHNE, OF BERLIN-CHARLOTTENBURG, GERMANY, ASSIGNOR TO DEUTSCHE TELEPHONWERKE UND KABELINDUSTRIE AKTIENGESELLSCHAFT, OF BERLIN, GERMANY

SLUICE FOR TUBULAR DISPATCH SYSTEMS

Application filed March 14, 1929, Serial No. 246,875, and in Germany June 8, 1926.

The present invention relates to a conveying tube sluice for tubular dispatch systems which substantially consists of a chamber provided on both sides with automatic closures, and from which chamber the container passes to the outside after having passed through both closures. Such a double sluice is adapted to effect the discharge of the container from the conveying tube in such a manner that the compressed air cannot pass directly into the atmosphere, or when operating with suction air the atmospheric air cannot directly enter the conveying tube, but can only flow into the sluice chamber from which it is then sucked by the blower. In the known sluices of this type (see German specification 359034) the closures are constructed in the form of flaps which are opened by the incoming container by a feeler lever and after the passage of the container are returned into the closing position by a weight or by spring action.

According to the present invention the closure members of the chamber are no longer in the form of simple hinged flaps, but in the form of sliding flaps which are located with a slight gap between two oppositely disposed ends of the conveying tube and are hingedly connected to their operating lever so that the sliding flap is caused to bear automatically in a fluid tight manner against one or other end of the conveying tube, according as to whether the operation is being effected by compressed air or by suction, by the action of the pressure ratio set up during the operation. In comparison with the above earlier flaps and the large amount of space required therefor a considerable simplification is obtained in this manner.

At higher pressures the known device for relieving the load from the sliding flap is preferably used so that such flap is only subjected to load at the times at which it is in the closing position, whilst it is relieved of load when it is required to be moved. In connection with the upper closure first reached by the container this relieving of load is effected in the known manner by throttling equalizing apertures which form communication between the sliding flap chamber and

the portion of the conveying tube located in front of such flap, whilst in connection with the lower closure the relieving of the load is effected by a pressure equalizing valve which is opened in the known manner by the container passing through the sluice chamber by means of a feeler lever and the like.

As the sliding flap is arranged so as to be freely movable its frictional resistance is very low. Consequently it is also possible to provide the sliding flap with a leather or rubber covering and so forth in order to obtain an efficient fluid-tight closure in the closing position.

The invention is illustrated in the accompanying drawing. The figures only show the upper sliding flap of the two sliding flaps of the double sluice, the lower sliding flap being assumed to be constructed in a similar manner.

Within the chamber K closed on all sides the openings m^1 and m^2 of the incoming conveying tube F^1 and the outgoing conveying tube F^2 are opposite one another. Between the two there is located a sliding flap or closure member S, formed for example as a hollow body, which is withdrawn towards the right against the action of the spring f by means of an arm e pivotally mounted at d when the incoming container pushes the feeler lever h laterally, this lever being secured to the shaft d. By reason of the pin and slot connection n the arm e is capable of moving in an arc whilst the sliding flap S can move horizontally. It will be understood that by virtue of the said pin and slot connection the sliding flap S may also have a movement toward and from the openings m_1 , m_2 at the neighboring ends of the tubes F_1 , F_2 respectively, to bear tightly against one or the other of said ends, and to seal it. This movement lengthwise of the gap between the tube ends is obtained by differences in air pressure. The sliding flap S is shown in Fig. 1 in such an air supported position sealing the upper tube-opening. The sliding flap S is supported in the withdrawn position by the roller t. Said flap will not disengage from this roller until it has been completely moved into the gap, and then

seats itself on one tube end or the other, as described. Such a support is unnecessary when the pivotal point of the sliding flap is supported by two springs as shown in Figure 2, tending to hold it in the middle of the gap between the two conveying tubes. The lateral movement of the sliding flap is limited by the stops v^1, v^2 . The sliding flap may be smooth and ground, it may also, as hereinbefore described, be provided with a covering of leather, rubber or the like for obtaining a fluid-tight joint. This construction as a rule renders it necessary even with small pressures to relieve the load from the sliding flap, as described above, so as to enable it to be withdrawn. A sliding flap with rubber packing is shown by way of example in Figure 2. The sliding flap is of wedge shape and is provided for the purpose of strengthening it with a metal insertion B and its front edge with a metal protecting covering P, by means of which it slides over the openings of the conveying tubes. For the purpose of obtaining free movement the pivot of the pin-and-slot connection N is mounted in the slot of the operating lever C by means of two springs H. The stop V is shown adjustable in Fig. 2, so as to variably limit the transverse movement of the sliding flap in the gap between the open tube ends.

The mechanism for moving the sliding flap may be constructed in any suitable manner. The drawings show the simplest form of construction by means of which blows in the rod mechanism are eliminated.

The single chamber with the sliding flap can also be used as a passing station or a closure for a conveying tube without the second chamber.

I claim:

1. In a sluice for a conveying tube of a tubular dispatch system the combination with the open end of said tube of a closure member adapted to be freely movable between oppositely disposed openings of said conveying tube, said closure member being adapted to move from one of said openings to the other, to bear in a fluid-tight manner against one of the openings of said conveying tube by reason of the pressure acting thereon, said closure member being also movable transversely and means for actuating said closure member in a transverse direction, said means including a shaft, a lever secured to said shaft and projecting into said tube into the path of a container adapted to pass therethrough, a second lever keyed at one end to said shaft, a pin and slot connection between the other end of said lever and said closure member, and a spring acting upon said levers and normally holding them in a position in which the first mentioned lever projects into the path of the container when the second mentioned lever

holds the closure member in its closed position.

2. In a sluice for a conveying tube of a tubular dispatch system the combination with the open end of said tube of a closure member adapted to be freely movable between oppositely disposed openings of said conveying tube, said closure member being adapted to bear in a fluid-tight manner against one of the openings of said conveying tube by reason of the pressure acting thereon, and means for actuating said closure member, said closure member consisting of a rubber wedge, a layer of metal extending therethrough for strengthening purposes, and a metal tip over the forward end of said rubber wedge.

3. In a sluice according to claim 2, wherein springs are located in said slot and engage with said pin so as normally to retain the closure member in the median position.

4. In a sluice for a conveying tube of a tubular dispatch system, the combination of a sluice-chamber containing a small gap arranged in the conveying tube, a lever arranged for being swung by a container entering the sluice, a flat closure member consisting of an essentially rigid flap hingedly connected to the end of said lever and slidable within the said gap, the said gap being so dimensioned as to allow only the sliding in of the said flap but not of the said lever, and allowing a free movement of the said flap under the action of the operating air pressure in the direction of the axis of the conveying tube to and from the one and the other of the tube-openings lying adjacent to said gap, for effecting an air-tight closure of one or the other of such openings.

5. In a sluice for a conveying tube of a tubular dispatch system, the combination of a sluice-chamber containing a gap arranged in the conveying tube, a lever arranged for being swung by a container entering the sluice, a flat closure member consisting of an essentially rigid flap hingedly connected to the end of said lever and slidable within the said gap, the said gap being so dimensioned as to allow only the sliding in of the said flap but not of the said lever, and allowing a free movement of the said flap under the action of the operating air pressure in the direction of the axis of the conveying tube to and from the one and the other of the tube-openings lying adjacent to said gap, for effecting an air-tight closure of one or the other of such openings, the hinge point of the said flap being located in a slot provided in the said lever.

6. In a sluice for a conveying tube of a tubular dispatch system, the combination of a sluice-chamber containing a gap arranged in the conveying tube, a lever arranged for being swung by a container entering the

sluice, a flat closure member consisting of an essentially rigid flap hingedly connected to the end of said lever and slidable within the said gap, the said gap being so dimensioned as to allow only the sliding in of the said flap but not of the said lever, and allowing a free movement of the said flap under the action of the operating air pressure in the direction of the axis of the conveying tube to and from the one and the other of the tube-openings lying adjacent to the said gap, for effecting an air-tight closure of one or the other of such openings, a pin-and-slot connection between the said lever and the hinge point of said flap, and a system of springs arranged within said slot and adapted for normally holding the said hinge point in a median position.

7. In a sluice for a conveying tube of a tubular dispatch system, the combination of a sluice-chamber containing a gap arranged in the conveying tube, a lever arranged for being swung by a container entering the sluice, a flat closure member consisting of an essentially rigid flap hingedly connected to the end of said lever and slidable within the said gap, the said gap being so dimensioned as to allow only the sliding in of the said flap but not of the said lever, and allowing a free movement of the said flap under the action of the operating air pressure in the direction of the axis of the conveying tube to and from the one and the other of the tube-openings lying adjacent to said gap, for effecting an air-tight closure of one or the other of such openings, the hinge point of the said flap being located in a slot provided in the said lever, and means for supporting said flap during its movement into and out of the said gap.

8. In a sluice for a conveying tube of a tubular dispatch system, the combination of a sluice-chamber containing a gap arranged in the conveying tube, a lever arranged for being swung by a container entering the sluice, a flat closure member consisting of an essentially rigid flap hingedly connected to the end of said lever and slidable within the said gap, the said gap being so dimensioned as to allow only the sliding in of the said flap but not of the said lever, and allowing a free movement of the said flap under the action of the operating air pressure in the direction of the axis of the conveying tube to and from the one and the other of the tube-openings lying adjacent to said gap, for effecting an air-tight closure of one or the other of such openings, the hinge point of the said flap being located in a slot provided in the said lever, and a roller arranged adjacent to said gap, for supporting the said flap during its movement into and out of the gap.

9. In a sluice for a conveying tube of a tubular dispatch system, the combination of a sluice-chamber containing a gap arranged in the conveying tube, a lever arranged for be-

ing swung by a container entering the sluice, a flat closure member consisting of an essentially rigid flap hingedly connected to the end of said lever and slidable within the said gap, the said gap being so dimensioned as to allow only the sliding in of the said flap but not of the said lever, and allowing a free movement of the said flap under the action of the operating air pressure in the direction of the axis of the conveying tube to and from the one and the other of the tube-openings lying adjacent to said gap, for effecting an air-tight closure of one or the other of such openings, and adjustable means for variably limiting the sliding movement of the said flap in the said gap.

10. In a sluice for a conveying tube of a tubular dispatch system, the combination of a sluice-chamber containing a gap arranged in the conveying tube, a lever arranged for being swung by a container entering the sluice, a flat closure member consisting of an essentially rigid flap hingedly connected to the end of said lever and slidable within the said gap, the said gap being so dimensioned as to allow only the sliding in of the said flap but not of the said lever, and allowing a free movement of the said flap under the action of the operating air pressure in the direction of the axis of the conveying tube to and from the one and the other of the tube-openings lying adjacent to said gap, for effecting an air-tight closure of one or the other of such openings, the said flap being provided with a covering of elastic material.

11. In a sluice for a conveying tube of a tubular dispatch system, the combination of a sluice-chamber containing a gap arranged in the conveying tube, a lever arranged for being swung by a container entering the sluice, a flat closure member consisting of an essentially rigid flap hingedly connected to the end of said lever and slidable within the said gap, the said gap being so dimensioned as to allow only the sliding in of the said flap but not of the said lever, and allowing a free movement of the said flap under the action of the operating air pressure in the direction of the axis of the conveying tube to and from the one and the other of the tube-openings lying adjacent to said gap, for effecting an air-tight closure of one or the other of such openings, the said flap consisting of a rubber wedge, a layer of metal extending therein for strengthening purposes, and a metal tip covering the forward end of said rubber wedge.

12. In a pneumatic conveying system, a conveying tube having two portions with ends spaced from each other to form a gap, a casing enclosing said tube portions at their gap, a closure member movable transversely into and out of said gap, and also movable from one of said tube ends to the other, to seal either tube end, and mechanism located
